Des. 232,616
Patented Sept. 3, 1974

232,616

VACUUM CLEANER CASING

Richard A. Wareham, North Canton, Ohio, assignor to
The Hoover Company, North Canton, Ohio

Filed July 6, 1973, Ser. No. 377,048

Term of patent 14 years

Int. Cl. D15—05

U.S. Cl. D7—170

FIG. 2

FIG. 1

FIG. 3

FIG. 4

FIG. 5

FIG. 1 is a front perspective view of a vacuum cleaner casing shown in use with a handle and cleaner bag, which handle and cleaner bag are shown in broken lines for illustrative purposes only and form no part of the claimed design;

FIG. 2 is a top plan view thereof;

FIG. 3 is a side view thereof, shown with a set of wheels, which wheels are shown in broken lines for illustrative purposes only and form no part of the claimed design;

FIG. 4 is a front elevational view thereof, shown in use on a cleaner head which cleaner head is shown in broken lines for illustrative purposes only and forms no part of the claimed design;

FIG. 5 is a rear view of the claimed design as shown in FIG. 4.

I claim:

The ornamental design for a vacuum cleaner casing, as shown and described.
